UNITED STATES PATENT OFFICE

CHARLES S. HALL, OF COTTAGE GROVE, OREGON, ASSIGNOR OF ONE-THIRD TO HERBERT W. LOMBARD AND ONE-THIRD TO ARCHIE C. BAGLEY, BOTH OF COTTAGE GROVE, OREGON

DESIGN FOR A VENDING STAND

Application filed January 2, 1930. Serial No. 33,993. Term of patent 14 years.

To all whom it may concern:

Be it known that I, CHARLES S. HALL, a citizen of the United States, residing at Cottage Grove, in the county of Lane and State of Oregon, have invented a new, original, and ornamental Design for Vending Stands, of which the following is a specification, reference being had to the accompanying drawing, forming part thereof.

In the drawing

I claim:

The ornamental design for a vending stand, as shown.

CHARLES S. HALL.
